UNITED STATES PATENT OFFICE.

JOHN A. PEGG, OF JONESTOWN, MISSISSIPPI.

SHIPPING-TAG.

SPECIFICATION forming part of Letters Patent No. 340,455, dated April 20, 1886.

Application filed July 27, 1885. Serial No. 172,812. (No model.)

To all whom it may concern:

Be it known that I, JOHN A. PEGG, of 5
Jonestown, in the county of Coahoma and
State of Mississippi, have invented a new and
Improved Shipping Tag and Label, of which
the following is a full, clear, and exact descrip-
tion.

My invention relates to that class of devices
used for marking goods that are to be shipped
10 or transported from place to place; and the
invention consists of a metal tag or label in or
through which the shipping-marks are made
or punched, and in certain details of construc-
tion, as will be fully described, and specific-
15 ally pointed out in the claims, the tag or label
being especially adapted to the marking of
cotton-bales.

Reference is to be had to the accompanying
drawings, forming a part of this specification,
20 in which similar letters of reference indicate
corresponding parts in all the figures.

Figure 1 is a plan view of my improved form
of shipping-tag, showing the same as applied
25 to one of the ties of a cotton-bale. Fig. 2 is a
side view of the same, the bale and its cover
being shown in section. Fig. 3 is a sectional
view taken on line *x x* of Fig. 1, and Fig. 4 is
a view of the implement used for attaching
the tag.

30 Referring to the drawings, A represents a
metal plate, upon which the shipping marks,
devices, or address, *k k*, are stamped so as to be
in relief, or the plate may be indented, to form
the marks; but I greatly prefer to have the
35 marks cut entirely through the plate, which
is preferably made of tin, so that when the
tag or label is secured to the bale-tie B, in the
manner to be hereinafter described, the dark
body of the tie will show through the marks
40 cut in the tag, and thus render the device or
marks more conspicuous by reason of the
contrast between the white face of the tag and
the dark body of the tie.

Two of the sides of the tag or label are ser-
45 rated or otherwise indented, so as to form
prongs or points *i i*, and the sheet-metal plate
of which the tag is formed is bent downward
at *c c*, as best shown in Fig. 3, and each of the
flanges *b b*, formed by bending down the edges
50 of the plate, is bent inward and then outward,

so that the upper portion of the flange will pro-
ject beneath the tie B; but the prongs or
points *i i* will project outward from the inner-
most portion, *d*, of each flange, as clearly
shown in Figs. 2 and 3.

55 In order to attach my tag or label to the
bale-tie, I employ a pair of pliers, as C, that
are formed with wide jaws *e e*, between which
the tag may be inserted and grasped, as shown
in Fig. 4, when it is desired to secure the tag
60 to the tie, which is done by springing the
flanges formed on the two sides of the tag over
the tie, pressing portions *d* toward each other
by power applied to the lever-arms of the pli-
ers C, and in then releasing the tag, so as to
65 permit the points or prongs *i i* to enter the
fiber of the bagging *h*, that surrounds the bale
H, thus securing the tag to the bale in sub-
stantially the position shown in Fig. 3.

Having thus described my invention, what I
70 claim as new, and desire to secure by Letters
Patent, is—

1. A metallic tag or label consisting of a
plate with serrated edges on two opposite sides,
which are bent downwardly and inwardly
75 and then downwardly and outwardly, as set
forth.

2. A metallic tag or label consisting of a
plate having inwardly-projecting flanges *b d*
and outwardly-projecting points *i* on two op-
posite sides, substantially as described.

3. The combination, with the bale-cover and
the tie, of a metal tag or label in which two
opposite sides are bent downward, inward,
85 and outward, and the outwardly-projecting
portion is formed with points or prongs, sub-
stantially as described.

4. The combination, with the bale-cover
and the tie, of a metal shipping tag or label
in which the shipping marks or devices are
90 cut through the body of the tag, and in which
two opposite sides are bent downward, in-
ward, and outward, and the outwardly-projecting
portion is formed with points or prongs,
substantially as described.

JOHN A. PEGG.
